UNITED STATES PATENT OFFICE.

CHARLES D. RIGG, OF ALTOONA, PENNSYLVANIA.

BOW FOR MUSICAL INSTRUMENTS.

Application filed November 24, 1920. Serial No. 426,229.

To all whom it may concern:

Be it known that CHARLES D. RIGG, a citizen of the United States, residing at Altoona, in the county of Blair and State of Pennsylvania, has invented certain new and useful Improvements in Bows for Musical Instruments, of which the following is a specification.

This invention relates to stringed musical instruments and has particular reference to the bow construction of the violin, cello, viola, and double bass instruments.

A primary object of the invention is to provide a new and novel means of attaching the bow hair to both the frog and tip of the bow, whereby the hair can be readily and easily removed and replaced without destroying the utility of any of the hairs that go to make up the bow.

Another object of this invention is to provide means whereby all the hairs in the bow are placed under the same tension, when drawn to position by the musician.

A further object of the invention is to provide an additional tension device to be used with the bow hair, in combination with the usual tension adjustment now commonly used in connection with the frog of the ordinary bow.

A still further object of the device is to provide a plurality of metallic receptacles or clamps at the ends of the bow hair, which form the part of the bow that engages the various strings on the instrument to be played, one of such clamps being movable within the frog, for the purpose of securing the clamp and providing additional means for tightening the bow hairs in the bow.

With these and other objects in view which will more readily appear as the nature of the invention is better understood the same consists in the novel construction, combination and arrangement of parts herein-after more fully pointed out, illustrated and claimed.

It will, of course, be understood by those skilled in the art to which this invention relates that the same is quite susceptible of various changes and modifications without departing from the spirit or scope of the invention, but a preferable and thoroughly practicable application of the invention is shown in the accompanying drawings in which:

Figure 1 is an elevation of a violin bow having my invention applied thereto.

Figure 2 is an enlarged detail view of the tip end of the bow illustrating the means whereby the hairs are held in the tip end of the bow.

Figure 3 is an enlarged detail view of the frog end of the bow and illustrates the manner of securing the bow hairs in the frog, together with an additional means for adding tension to the hair in the bow.

Figure 4 is a detail view of the hair clamp that is adapted to be fitted into the tip of the bow.

Figures 5 and 5^a are respectively a detail view partly in section of the tip end of the bow, showing a receptacle for the bow hair clamp, and an inverted plan view of the tip end of the bow.

Figures 6 and 6^a are respectively a detail view partly in section of the frog end of the bow, illustrating the receptacle for the hair clamp, and an inverted plan view of the frog.

Figure 7 is an end elevation of the frog shown in Figure 6 of the drawings.

Figure 8 is a section of the frog taken on the line 8—8 of Figure 6.

Figure 9 is a perspective view of the open position of the bow hair clamp which is adapted to fit into the tip end of the bow as shown in Figure 2 of the drawings.

Figure 10 is a perspective view showing the closed position of the clamp, the various hairs being in position as when placed in position in the tip end of the bow.

Figure 11 is an open edge view of the bow hair clamp adapted to be fitted into the frog end of the bow, and shown in operative position in Figure 3 of the drawings.

Figure 12 is a side elevation of the clamp shown in Figure 11 and illustrates the manner of distributing the hair in the clamp, such that each hair will have the same tension when drawn to place on the strings of the instrument played by the musician.

Figure 13 is a closed edge view of the clamp shown in Figures 11 and 12 and illustrates the manner of securing the hair of the bow in the clamp.

Figure 14 is a detail view of a screw used in connection with the clamp shown in the frog end of the bow, and shown in position in Figure 3 of the drawings.

Figure 15 includes plan and edge views of the cover plate used to cover the opening in the frog; after the hair clamp is in position as shown in Figure 3 of the drawings.

Figure 16 includes a plan and elevation of a ferrule forming a part of the frog, and used as a housing for a wood wedge over which the hairs pass that emerge from the 5 clamp in the frog.

Similar reference numerals refer to similar parts throughout the several figures of the drawings.

In carrying out this invention no change 10 is contemplated in the usual construction of the violin bow, and the tip and frog as commonly constructed, can, with a slight modification be made to receive the elements 15 of this invention and to this end I follow the usual construction of the bow designated by the numeral 10, the same having a tip 11, a frog designated in its entirety by the numeral 12, and bow hairs 13 adapted to be drawn taut between the tip 11 and the frog 20 12 as shown in Figure 1 of the drawings.

In the face 14 of the bow tip 11 I provide a recess or tip socket 15, into which may fit a threaded nut plate 16, which is engaged by a screw 17. The said recess 15 25 is adapted to receive a compressible clamp 18, having a transverse groove 19 on its outer face, which is adapted to receive the inner end of the screw 17 to hold the clamp 18 in its place in the recess 15. In applying 30 the clamp 18 to the bow hairs 13, the hairs or strands forming a part of the bow are tied into a knot 20 which is forced into the opening 21, preferably made circular in shape at the junction of the jaws 22 and 23 35 of the clamp 18. The knot 20 in the bow hair 13 having been placed in the circular opening 21 the clamp jaws are closed as shown in Figure 10 of the drawings. The jaws having been closed a cementing preparation such as rosin, is placed around the 40 hairs in the clamp to assist in holding the same in place. The hairs as they emerge from the clamp are spread out such that the clamp can be readily closed, thus holding 45 the hair in place and at the same time provide adequate means whereby the hairs or strings are all evenly distributed over the face of the clamp jaw, which is quite essential in order to obtain an equal tension on 50 each of the hairs.

The frog 12 is likewise provided with a recess, which is adapted to receive a frog clamp 25. The clamp is provided with means for holding a knotted end 26 in the 55 bow hair 13, after which the hairs are spread out evenly over the face of the jaw 27. The jaws 27 and 28 are then closed upon the strings as shown in Figure 13 of the drawings, and a cementing solution is applied 60 to the portion of the hairs within the clamp for the purpose of binding the same together.

The jaw 27 of the clamp 25 is provided with a projecting central lug 29, which is 65 threaded to receive a tension anchor screw

30, that is designed to pass through an opening 31 in the frog 12, and engage the threaded lug 29 and enter a smaller diameter drilled hole 32 in alignment with the opening 31. The screw 30 is provided with an 70 extension 33 that is not threaded which allows better facilities for alining the clamp with the bow.

For the purpose of covering the recess 24, there is provided a slide 35 which is adapted 75 to coat with a suitable groove 36 in the face 37 of the frog as shown in Figure 6 of the drawings.

And to provide a finish for the face of the frog where the bow strings emerge, there 80 is provided a ferrule 38, which is shown in place in Figure 3. The ferrule is flattened on one side in alignment with the face of the frog while it is further fitted with a wooden wedge 39 which acts as a bridge over which 85 the hairs that form the bow pass.

In the manufacture of these improved bows, it is proposed to construct the tip and frog of the bow as above explained and to provide the bow hair with the tip and 90 frog clamp attached and the restringing of the bow will be only a matter of a few seconds while at the present time the rehairing requires several hours. I have thus produced an article of manufacture that is not 95 only novel and durable but it saves the time of the musician and manufacturers as well.

I claim:

1. A detachable and replaceable bow string construction including in combination with 100 the bow having tip and frog sockets, a bow string, and a removable tip clamp unit including two relatively compressible jaws for clamping the string, and means carried by the bow for holding said tip clamp in the 105 tip socket of the bow and also maintaining the jaws of said clamp in engagement with the string.

2. A detachable and replaceable bow string construction including in combination 110 with the bow having tip and frog sockets, a bow string having a tip clamp at one end and a frog clamp at the other, said frog clamp having relatively compressible jaws for gripping the frog end of the string, and 115 one of said jaws carrying a nut element, a slide for covering the frog socket and constituting a wall against which one of the jaws of the frog clamp impinges, and a screw for engaging with the nut element to 120 shift the clamp longitudinally in the socket.

3. A frog clamp construction for bow strings including in combination with a frog socket, a screw spanning the socket and having its head portion exposed at the outside 125 of the frog for manipulation, a clamp for the frog end of the string consisting of relatively compressible clamping jaws, a nut element carried by one of said jaws and engaging the screw whereby said jaw 130

is held relatively fixed with reference to the plane of movement of the other jaw, and a sliding cover for the socket of the frog adapted to engage with the other jaw of the 5 clamp thereby to maintain it in relatively compressed relation to the other jaw for gripping the end of the bow string.

4. A detachable and replaceable bow string construction, including in combination, a bow having tip and frog sockets, a bow string, a tip clamp fitted in the tip socket of the bow, means for holding the same in position, a frog clamp engaging one end of the string and fitting in the frog socket, 10 and means carried by the frog and engaging the frog clamp for shifting the same longitudinally in the frog socket to regulate the tension on the string.

5. A bow string construction including a 20 bow having a tip socket, a compressible clamp consisting of opposite spring jaws

for receiving and clamping one end of the string, one of said jaws having a groove in its outer face, and means carried by the tip of the bow and projecting into the tip socket 25 for engaging with the groove in the clamp to hold the same in the socket and also compress the jaws thereof to securely grip the end of the string.

6. A bow string construction including 30 a bow having a frog socket, a bow string fitted at one end to the tip of the bow, a frog clamp of substantially U-shaped character adapted to grip the frog end of the string, a nut element carried by the frog 35 clamp, a screw carried by the frog and adapted to engage the nut element of the frog to shift the latter in the frog socket to adjust the tension on the bow string.

In testimony whereof I have affixed my 40 signature.

CHARLES D. RIGG.
